UNITED STATES PATENT OFFICE.

WILLIAM ORR, OF TRENTON, NEW JERSEY, ASSIGNOR TO THE NEW JERSEY
WIRE CLOTH COMPANY, OF SAME PLACE.

FIREPROOF CONSTRUCTION.

SPECIFICATION forming part of Letters Patent No. 598,481, dated February 1, 1898.

Application filed May 1, 1896. Serial No. 589,838. (No model.)

To all whom it may concern.

Be it known that I, WILLIAM ORR, a citizen of the United States, residing at Trenton, county of Mercer, and State of New Jersey, have invented certain new and useful Improvements in Fireproof Constructions, fully described and represented in the following specification and the accompanying drawings, forming a part of the same.

10 The object of the present invention is to provide an improved fireproof construction especially adapted for partition-work, but which may be used also for walls, ceilings, roofs, and in similar constructions.

15 The present invention enables such fireproof constructions to be produced in a more efficient and economical manner than heretofore, while at the same time the desired durability and efficiency are secured, these results being obtained by the use of slabs of suitable plastic material secured at the ends to other parts of the construction and preferably attached together at their side edges, so as to form a continuous partition-wall or

20 other construction of the requisite strength. These fireproof slabs are preferably provided with a metallic frame embedded therein—such as wire lathing, perforated sheet metal, or wire—which forms a bond for the plastic material, greatly strengthening the construction.

25 For the purpose of securing these slabs to fixed parts of the construction, so as to hold them in place, metallic connections are embedded in the plastic material and extend beyond the end or ends of the slabs, and these metallic connections are preferably extensions of the metallic frame, which forms a bond for the plastic material, as above described, when such a frame is employed.

30 These metallic connections need not extend throughout the length of the slabs, however, but may be only of such length as to secure the hold upon the plastic material of the slabs required for securing the slabs in place. Such

35 metallic connections also may be provided on one or both the side edges of the slabs, so as to be used in securing adjacent slabs together or in securing the slabs in place by their side edges; but other means may be used for this

40 and wall constructions, the slabs may not be secured together at their side edges.

The metallic frame embedded in and forming a bond for the plastic material is preferably the common woven or twisted wire 55 lathing, this forming a most efficient bond and a very convenient means of securing the blocks in place or to each other, in the manner hereinafter described, when it is extended beyond the edges of the slabs. As above 60 stated, however, any other suitable form of metallic lathing may be used, or separate wires will be found quite efficient when embedded in the material, and such wires may extend either longitudinally or crosswise of 65 the slab or in both directions. The use of two or more such wires extended beyond the edges of the slabs to form the metallic connections for the slab, in combination with wire lathing forming a bond for the plastic 70 material, constitutes a very efficient and convenient construction.

In securing the slabs together at their side edges it is desirable that the connections do not project beyond the face of the slab, so 75 that in finishing only a thin coat of plaster need be applied to form a perfectly smooth uniform surface throughout the partition or other construction. This result is attained in accordance with the present invention by 80 providing the slabs with recesses at their edges to receive the connections by which the slabs are secured together.

The invention includes also a partition or other construction formed of plastic slabs 85 extending the full height of the partition, or the full length between supports in the case of walls, ceilings, or similar constructions, so as to be secured to fixed parts of the construction at their ends and secured in place 90 or to adjacent slabs, as hereinafter described, such a construction being very cheap and especially desirable for light solid partitions. In this construction a metallic bond for the plastic material, such as woven wire or perforated sheet metal or separate wires, is preferably used for the purpose of binding the plastic material together; but such a construction is of value under many circumstances without the metallic bond in the slabs. 100

For a full understanding of the invention a detailed description of a construction embodying all the features of the same in their preferred form and certain modifications 5 thereof will now be given in connection with the accompanying drawings, forming a part of this specification, and the features forming the invention will then be specifically pointed out in the claims.

- 10 In the drawings, Figure 1 is a side view, partly broken away, of a partition and ceiling construction embodying the invention and shown complete, with the exception of the light coat of finishing-plaster which is applied to cover the connections between the blocks, this figure showing the partition as composed in part of single blocks extending the full height of the partition, as preferred, and in part of shorter blocks connected at 15 their ends, adjacent blocks being connected together at their edges. Fig. 2 is a view on the line 2 of Fig. 1, partly in elevation and partly in section. Fig. 3 is a horizontal section on the line 3 of Fig. 1, showing the manner in which the blocks are connected together at their side edges. Fig. 4 is an edge view of a portion of one of the blocks, looking to the left in Figs. 1 and 3. Fig. 5 is a vertical section on the line 5 of Fig. 1, showing another method used in securing the blocks together at their ends. Figs. 6 and 7 show in 20 plan and cross-section other methods of securing the slabs together at their side edges, the sections being taken on the dotted lines 25 in the plan views. Fig. 8 shows a portion of a slab with woven-wire bond and attaching-wires running longitudinally through the slab. Fig. 9 shows in plan and longitudinal section a slab having two series of wires forming the bond and running at right angles to each other and projecting beyond the slab at all four edges for attachment. Fig. 10 shows another form of recessed slab, omitting the metallic bond and which may be used either 30 with or without attaching connections embedded in the slab.

In the drawings, A are the ceiling-beams, shown as of the common I form, and B the floor, between which and the ceiling-beams the partition is to be formed, the partition being shown as running longitudinally of a beam and secured to the bottom flanges thereof, the ceiling also being supported by these flanges. As shown at the left-hand portion of Fig. 1 50 and in Fig. 2, the partition is formed of long slabs C, continuous from floor to ceiling and secured at the top end to the beams A and at the base end to the floor B. As shown in this figure, which illustrates the preferred form 55 of these slabs, they are composed of plastic material of any suitable character having the requisite strength and have a metallic frame running through the center, which forms a bond for the plastic material, this bond being 60 formed, preferably, of woven or twisted wire lathing, as shown, and this wire lathing extends beyond the opposite ends of the slab,

so as to form means for attaching the latter in place to the beams A and to the floor B. This attachment of the lathing 10 may be 70 made in any suitable manner; but a simple, convenient, and efficient construction is shown, in which the wire lathing is secured at the top end of the slabs to similar wire lathing 11, running through the ceiling-slabs 75 D, which extend from beam to beam and are supported thereby, these slabs D being shown as formed in the same manner as the slabs C of the partition. The metallic lathing 11 of the slabs D on one side of the beam A is extended below the lower flange of the beam A and secured to the slab D on the opposite side of the beam by staples or nails 1, so as to form a loop of the lathing below the flanges of the beam, which supports plastic material to cover 80 and protect the beam, and to this loop of the lathing the lathing 10 of the slabs C is secured by wire ties 2 or in any other suitable manner, plastic material 3 then being filled in around the tops of the slabs C and the beam-flanges, which plastic material is held by the lathing 10 11, so as to firmly secure the tops of the slabs C in place and form a continuous partition.

At the base the slabs C are recessed to form 95 grooved edges, which are entered by a rib 12 on the floor B, so as to partially secure the partition-slabs in place, these grooves and the rib preferably being made angular, as shown, for strength. The slabs are permanently secured in place and firmly held, preferably by cutting the lathing at intervals at the base of the slab and bending successive sections of the lathing in opposite directions, as shown at the edge of the slab in Fig. 4, the lathing 105 projecting from the base of the slab sufficiently to be secured by staples or nails 1 to the floor B. The lathing may all be bent to one side without cutting, however, and the slabs secured on only one side, or the slabs 110 may be secured in any other suitable manner.

The slabs are preferably secured together at their side edges for strength and to form a continuous practically-integral partition, and for this purpose the construction shown 115 clearly in Figs. 1 to 3 is preferably used, in which one edge of each slab is cut away to form a rib, preferably angular, as shown, and the opposite edge is similarly grooved to receive the rib edge of the next slab, and each 120 slab is provided at intervals on the rib edge with recesses 4, preferably arranged alternately on opposite sides of the slab, as shown, and forming depressions below the face of the slabs, which receive strips of the lathing 125 10, which is cut at intervals corresponding to the recesses 4 and bent in opposite directions, so as to lap over the opposite sides of the next slab and be secured within the recesses 4 by staples or nails 1, as shown clearly 130 in Fig. 3, this construction securing the slabs together firmly and at the same time leaving but a small space to be filled up for forming a smooth surface in completing the partition,

as the connections do not project outside the face of the slabs.

As above stated, the use of slabs each of which extends the full height of the partition is preferred, as this construction is cheaper, simpler, and stronger; but it is possible to use shorter slabs secured together at their ends, and such a construction is shown at the right hand in Fig. 1. These shorter slabs are of the same construction as previously described and shown at the left hand in Fig. 1; but the lathing in adjacent slabs is arranged near the opposite faces, and each slab is recessed throughout the whole or part 15 of its end next the adjacent slab and on the side opposite that at which the lathing is placed, so as to receive the end of the lathing 10 of the next slab. The lathing projects beyond the ends of each slab sufficiently to 20 loop over and be secured in the recessed end of the next slab by staples or nails 1, as shown, and the ends of the slabs are thus connected together on two lines, so as to secure a much more rigid construction than if 25 secured together on only one line, while the lathing does not project outside the faces of the blocks and leaves but a small space to be filled up in finishing the partition, as previously pointed out in connection with the attachment of the slabs together at their side edges. This feature of securing the slabs together along two lines is of especial importance when slabs are to be secured together at their ends to form a long slab; but it may 30 be used also for securing the slabs together at their side edges, and in many cases will be found very desirable for such use.

After the partition has been constructed as described and shown it is covered throughout 40 from top to bottom with a coating of plaster sufficient to secure the desired finish, fill up all recesses, and cover completely the wire lathing, staples, &c. It will be seen that by this construction a partition of perfectly 45 smooth uniform surface throughout is readily secured without applying a thick coating of plaster except at the points necessary to fill up the recesses and cover the ends of the lathing and staples or nails, and but a small 50 amount of such thick filling is required. With this slab partition or a wall or ceiling similarly formed it will be understood that any detail additions may be made, the same as in the case of fireproof constructions made 55 by other methods. Thus, as shown, the usual blocks of wood or similar material 13 near the top and bottom of the partition, for the attachment of the picture-molding and base-boards, are provided by molding the blocks 60 into the plastic slabs in process of manufacture or otherwise, as desired.

While the slabs are preferably secured together at their side edges in the manner shown in Figs. 1 to 4 and previously described or 65 as shown in connection with the ends of the slabs in Fig. 5, as either of these forms a very strong and efficient construction, it will be

understood that they may be secured together by many other different methods, some of which embodying features of the invention 70 are shown in Figs. 6 and 7.

In Fig. 6 is shown a construction in which the slabs are recessed at intervals at their adjacent edges, these recesses forming depressions below the face of the slabs, which 75 receive plates of metal or wood or strips of lathing 14, which are stapled or nailed to the adjacent slabs by staples or nails 1, so as to hold them together. Fig. 7 shows a construction similar to Fig. 6, except that separate 80 plates of metal are not used; but the slabs are secured together within similar recesses at their adjacent edges by staples 7 of sufficient size and strength to hold the two slabs together firmly. 85

Other methods may be used for the purpose of securing the slabs together at their side edges, but the forms shown are sufficient to illustrate the invention and to suggest to those skilled in the art many other modifications. 90

As above stated, other means than woven or netted wire or perforated metal lathing extending beyond the ends of the slabs may be used for the purpose of securing the slabs 95 in place, and an efficient and convenient construction for this purpose is obtained by using wires of suitable size embedded in and preferably running through the slabs and projecting beyond one or more of the edges of 100 the slabs sufficiently to form ties by which the slabs may be attached to other parts of the construction and held in place or attached to each other. These wires may be used either with or without another bond, such as 105 wire or perforated metal lathing, but preferably will be used with the other bond, especially if wires running in but a single direction through the slabs are used, as the slabs are thus made very strong by the bond which 110 the wire or perforated metal lathing gives, and only enough separate wires to hold the slabs in place need be used.

In Fig. 8 is shown a part of a slab C similar to those previously described, except that 115 the metallic lathing 10 does not extend beyond the end of the slab; but the attachment of the slab in place is secured by three wires 15, which preferably extend the full length of the slab and beyond the latter at both ends a 120 short distance, as shown, for attachment of the slab to other parts of the construction.

In Fig. 9 is shown a construction in which the slabs are provided with wires 15, running through the slab in opposite directions and 125 extending beyond the slab at all four edges, so as to form means by which the slabs may be attached in place at their opposite ends and at their side edges to other slabs or other parts of the construction. As shown in this 130 figure, the metallic lathing is omitted, the wires being depended upon to secure the requisite bond of the plastic material, and the wires extending sidewise through the

slabs are shown as staggered, so as to be arranged in two series near the opposite edges of the slab, which provides convenient means for securing adjacent slabs together at opposite side edges and secures two lines of attachment transversely to the slab, making a much stronger construction than where all the attachments are in a single line. It will be understood that these wires 15, whether used with or without the metallic lathing, may be corrugated, twisted, ribbed, or formed in any other suitable manner, so as to secure the tensile strength of the wire transversely to the slab or to obtain a stronger hold upon the plastic material. While the wires 15 have been shown as the ordinary round wire, it will be understood that flat strips of metal may be used as an equivalent construction.

While the metallic lathing, wires, or some similar bond for the plastic material is preferably used, the invention includes also a partition, wall, ceiling, &c., formed of plastic slabs secured together at their edges on opposite sides of the center by connections in depressions in the faces of the slab, so that the connections do not project outside of the face of the slab whether the metallic bond be used or not, and certain constructions employing plastic material slabs with or without such bonds.

In Fig. 10 I have shown a slab which is desirable for use where a thick partition or other construction with air-spaces is required, these slabs C being provided with recesses forming depressions below the face of the slab on their opposite side edges at intervals or throughout their entire length, so that adjacent slabs may be secured together by abutting their edges and applying within the recesses plates 14 similar to those shown in Fig. 6 and previously described, which are then secured to the two slabs by nails or staples 1. The air-spaces may extend the full length of the slab, but to prevent their becoming a continuous flue in case of fire cut-offs may be made at one or more points in their length.

It will be understood that many other modifications may be made in the constructions shown embodying the invention and that I am not to be limited to the exact form or arrangement of parts in any of the constructions shown.

What I claim is—

1. A slab for partitions, walls, ceilings, and other constructions, formed of plastic material and having metallic connections projecting beyond one or more edges of the slab for securing it in place or to other slabs, and having depressions below the face of the slab at one or more of its edges for receiving metallic connections projecting from the edge or edges of adjacent slabs, substantially as described.

2. A slab for partitions, walls, ceilings, and other constructions, formed of plastic material and having metallic connections project-

ing beyond one or more edges of the slab for securing it in place or to other slabs, said metallic connections being placed on one side of the center of said slab and the face of the slab on the opposite side of the center being recessed at the edge to receive the metallic connections from the next slab, substantially as described.

3. A slab for partitions, walls, ceilings and other constructions, formed of plastic material with a metallic bond embedded therein and projecting beyond one or more edges of the slab for securing it in place or to other slabs, said metallic bond being placed on one side of the center of said slab and the face of the slab on the opposite side of the center being recessed at the edge to receive the metallic connections from the next slab, substantially as described.

4. A slab for partitions, walls, ceilings and other constructions, formed of plastic material with metallic lathing embedded therein to form a bond for the plastic material and having separate wires embedded therein and projecting beyond one or more edges of the slab to form ties or fastenings for the slab, substantially as described.

5. A slab for partitions, walls, ceilings and other constructions, formed of plastic material and having a series of separate wires embedded therein, and a second series of separate wires embedded therein and crossing the wires of the first series, the wires of said second series being arranged alternately and entirely on opposite sides of the wires of the first series and on opposite sides of the center of the slab and projecting beyond the edges of the slab to form ties or fastenings for the slab near opposite faces of the slab, substantially as described.

6. A slab for partitions, walls, ceilings and other constructions, formed of plastic material and having metallic connections projecting beyond one or more edges of the slab for securing it in place or to other slabs, and having the face of the slab at the edge or edges opposite the edge or edges having the metallic connections recessed alternately on opposite sides of the slab to receive the metallic connections of the adjacent slab or slabs, substantially as described.

7. A slab for partitions, walls, ceilings and other constructions, formed of plastic material with metallic lathing embedded therein and projecting beyond the edge or edges of the slab, and the edge or edges of the slab from which the lathing projects being grooved, and the opposite edge or edges being cut away to form ribs, substantially as described.

8. A slab for partitions, walls, ceilings and other constructions, formed of plastic material with metallic lathing embedded therein and projecting beyond the edge or edges of the slab, and the edge or edges of the slab from which the lathing projects being

grooved, and the opposite edge or edges being cut away to form ribs, and the face of the slab adjacent to such ribbed edge or edges being recessed alternately on opposite sides of the slab, substantially as described.

9. A partition, wall, ceiling, or similar fire-proof construction formed of slabs of plastic material secured at their ends to suitable supports and having their side edges abutted and secured together by connections on opposite sides of the center plane of the slabs, substantially as described.

10. A partition, wall, ceiling, or similar fire-proof construction formed of slabs of plastic material secured at their ends to suitable supports and secured together at their side edges by connections in depressions below the faces of the slabs, substantially as described.

11. A partition, wall, ceiling, or similar fire-proof construction formed of slabs of plastic material secured at their ends to suitable supports and secured together at their side edges on opposite sides of the center of the slabs by connections in depressions below the faces of the slabs, substantially as described.

12. A partition, wall, ceiling or other fire-proof construction formed of slabs of plastic material extending the full height of the construction and secured at the opposite ends to suitable supports and having their side edges abutted and secured together by connections on opposite sides of the center plane of the slabs, substantially as described.

13. In a fireproof construction, a series of slabs of plastic material secured together at their edges on opposite sides of the center of the slabs by connections in depressions below the faces of the slabs, substantially as described.

14. In a fireproof construction, a series of slabs of plastic material secured together at their edges on opposite sides of the center of the slabs by metallic connections embedded in the slabs, substantially as described.

15. In a fireproof construction, a series of slabs of plastic material secured together at their edges by metallic connections embedded therein and projecting beyond the edges of the slab, the connections in adjacent slabs being placed near opposite faces of the slabs, substantially as described.

16. In a fireproof construction, a series of slabs of plastic material secured together at their edges by metallic connections embedded therein and projecting beyond the edge of the slab, the metallic connections at the edge of one slab being divided and lapped over the opposite faces of the adjacent slab or slabs, substantially as described.

17. In a fireproof construction, a series of slabs of plastic material having metallic connections embedded therein and projecting beyond the edge of the slab, the connections being divided and turned outward in opposite

directions for securing the slab in place or to other slabs, substantially as described.

18. In a fireproof construction, a series of slabs formed of plastic material with metallic lathing embedded therein to form a bond for the plastic material and projecting beyond the edge of the slab, the projecting portion of the lathing being divided into sections and lapped over the opposite faces of the adjacent slab or slabs, substantially as described.

19. In a fireproof construction, a series of slabs of plastic material having connections formed of metallic lathing embedded therein and projecting beyond the edge of the slab, the projecting portion of the lathing being divided into sections and turned outward in opposite directions for securing the slab in place or to other slabs, substantially as described.

20. In a fireproof construction, a series of slabs of plastic material secured together at their edges by metallic connections embedded therein and projecting beyond the edge of the slab, the edges from which the connections project being grooved, and the opposite edges being cut away to form ribs to extend into the grooves in the edges of the adjacent slabs, substantially as described.

21. In a fireproof construction, a series of slabs of plastic material secured together at their edges by connections formed of metallic lathing embedded therein and projecting beyond the edge of the slab, the edges from which the lathing projects being grooved, and the opposite edges being cut away to form ribs to enter the grooves in the edges of the adjacent slabs, the projecting lathing being divided into sections and lapped over the opposite faces of the adjacent slabs, substantially as described.

22. In a fireproof construction, a series of slabs of plastic material secured together at their edges by connections formed of metallic lathing embedded therein and projecting beyond the edge of the slab, the edges from which the lathing projects being grooved, and the opposite edges being cut away to form ribs to enter the grooves in the edges of the adjacent slabs, and the face of the slab adjacent to such ribbed edge being recessed alternately on opposite sides of the slab, the projecting lathing being divided into sections corresponding to the recesses in the faces of the adjacent slabs and lapped over the opposite faces of the adjacent slabs and secured in the recesses, substantially as described.

In testimony whereof I have hereunto set my hand in the presence of two subscribing witnesses.

WILLIAM ORR.
